THREAD-HANDLING MECHANISM FOR
SEWING MACHINESRudolph J. Sailer, Townley, N. J., assignor to The
Singer Manufacturing Company, Elizabeth,
N. J., a corporation of New Jersey

Application March 14, 1933, Serial No. 660,609

10 Claims. (Cl. 112—242)

This invention relates to improvements in sewing machines and more particularly to the thread-handling mechanism therefor.

One of the objects of this invention is to provide improved slack-thread producing mechanism whereby a reserve length of thread is drawn from the thread-supply through the tension when the work is shifted relative to the needle, the needle being then out of the work and an additional reserve length of thread is drawn from the thread-supply for the succeeding stitch-forming cycle.

With the above and other objects in view, as will hereinafter appear, the invention comprises the devices, combinations, and arrangements of parts hereinafter set forth and illustrated in the accompanying drawings of a preferred embodiment of the invention, from which the several features of the invention and the advantages attained thereby will be readily understood by those skilled in the art.

In the drawings:

Figure 1 is a front elevation of a sewing machine of the well known "Singer" type embodying the present improvements.

Figure 2 is a rear elevation of the head of the sewing machine showing the present improvements fixed thereto.

Figure 3 is a left end elevation of the same. The machine shown in the drawings is that type of machine known commercially as the "Singer" 149 Class machine, and comprises the usual base 1 from which rises the hollow upright member 2 formed with a laterally overhanging bracket-arm 3 terminating in a head 4. The head 4 is formed with bearing blocks 5 and 5' in which are journaled the usual presser-bar 8 provided with a presser-device 8' and reciprocating needle-bar 6 carrying needles 7 and provided with the usual tension-plate 7'. Located below the work-supporting plate 9 are the thread-carrying loops 10 which cooperate with the needles 7 in the formation of stitches.

When shifting the work relative to the needles it is necessary that a supply of slack-thread be provided in order that the material being acted upon may be shifted without puckering or gathering the material. After the material has been shifted it is necessary that an additional supply of slack-thread be provided to prevent the thread from being broken during the succeeding stitch-forming cycle. To this end I have provided a double acting slack-producing thread-arm which supplies slack needle-thread when the presser-foot is raised preparatory to shifting the

work and which supplies also additional slack needle-thread when the presser-foot is lowered preparatory to the first stitch-forming cycle.

In the illustrated embodiment my improved slack-thread producing mechanism comprises a thread pull-off arm 11 having thread-eyes 11' through which the needle-thread is led. The arm 11 is fixed to one end of a pivot-pin 12 which is journaled in and extends through the head 4 of the machine and to the other end of the pivot-pin is fixed a depending arm 13 formed with a V-shaped cam-portion 14. Fixed to the presser-bar 8 by the set-screw 15 is an L-shaped arm 16 to which is fixed by the screws 17 a wedge-shaped finger 18 which cooperates with the V-shaped portion 14 on the arm 13. Carried by the L-shaped arm 16 is a plunger 19 urged against the arm 13 by the coiled spring 20.

The presser-bar 8 is raised and lowered by the usual finger-lever 21 having a cam-portion 22 which engages the roller 23 carried by the member 24 which is fixed to the presser-bar. A pin 25 carried by the member 24 has pivoted thereto the presser-bar lifting rocker-arm 26 which is under control of a treadle (not shown). The above described raising means for the presser-bar are old and well known and further description is deemed unnecessary.

From the foregoing description it will be observed that upon raising the presser-bar and presser-foot the wedge-shaped finger 18 engages the V-shaped portion 14 of the arm 13 and cams the arm 13 to the right as viewed in Figure 2. The movement of arm 13 causes the pivot-pin 12 and the slack-producing arm 11 to swing in a clockwise direction, as viewed in Figure 1, thereby pulling a supply of thread through the tensions 28 and 29. The tensions are released at this time by the usual and well known mechanism, for example, the tension-releasing mechanism as disclosed in the United States Patent No. 1,410,057, issued March 21, 1922, to Gatchell. Continued upward movement of the presser-bar causes the wedge-shaped finger 18 to ride over the peak of the V-shaped cam-portion 14 thereby permitting the arm 11 to return to its initial position due to pressure exerted by the spring-pressed plunger 19. Upon lowering the presser-foot the above described movements are repeated. From the foregoing it will be obvious that when the presser-foot is raised the arm 16 which carries the wedge-shaped finger 18 is moved to the position shown in dotted lines in Figure 2 and this movement of the arm 16 causes the arm 11 to move to the dotted line position shown in Figure 1, and thence

back to the full line position, and also when the presser-foot is lowered the arm 16 is moved to the full line position shown in Figure 2 and this movement of the arm 16 causes the arm 11 to again move to the dotted line position and thence back to the full line position, whereby a reserve length of thread is drawn from the thread-supply when the presser-foot is raised and an additional reserve length of thread is drawn from the thread-supply when the presser-foot is lowered.

Having thus set forth the nature of the invention, what I claim herein is:—

1. In a sewing machine, in combination, a thread-carrying needle, a presser-bar, means for raising and lowering said presser-bar, and means under control of said last named means for pulling a reserve length of needle-thread from the thread-supply when the presser-bar is raised and for pulling an additional reserve length of thread from the thread-supply when the presser-bar is lowered.

2. In a sewing machine, in combination, thread-carrying needles, a presser-device movable from operative to inoperative position, and mechanism for supplying slack needle-thread when said presser-device is raised to inoperative position and for supplying additional slack needle-thread when said presser-device is lowered into its operative position.

3. In a sewing machine, in combination, a reciprocating needle-bar, a thread-carrying needle carried by said needle-bar, a presser-bar, a presser-device carried thereby, means for raising and lowering said presser-bar, a thread pull-off lever, and mechanism connecting said presser-bar with said pull-off lever, said mechanism including means for causing said pull-off lever to draw a reserve length of needle-thread from the thread-supply when the presser-foot is raised and an additional reserve length of thread from the thread-supply when the presser-foot is lowered.

4. In a sewing machine, in combination, a thread-carrying needle, a presser-bar, means for raising and lowering said presser-bar, a member carried by said presser-bar, a thread pull-off lever, and mechanism connecting said member with said lever, said mechanism including means for causing said pull-off lever to draw slack-thread for the needle when the presser-foot is raised and additional slack-thread when the presser-foot is lowered.

5. A sewing machine having, in combination, a

thread-carrying needle, a presser-bar, means for raising and lowering said presser-bar, a pivot-pin, a needle-thread pull-off lever carried thereby, a second lever carried by said pivot-pin and a member carried by said presser-bar and having means for imparting to said second lever an oscillatory movement when the presser-foot is raised and a second oscillatory movement when the presser-foot is lowered.

6. A sewing machine having, in combination, a thread-carrying needle, a presser-bar, means for raising and lowering said presser-bar, a pivot-pin, a needle-thread pull-off lever carried thereby, a second lever formed with a V-shaped cam-portion carried by said pivot-pin, and a member carried by said presser-bar, said member having a wedge-shaped cam cooperating with the V-shaped cam-portion on said second mentioned lever.

7. The combination as claimed in claim 6 with means for maintaining said second mentioned lever in engagement with said wedge-shaped cam.

8. In a sewing machine, in combination, stitch-forming mechanism including a reciprocating thread-carrying needle and loop-taking means coordinated therewith, a presser-foot movable in opposite directions to and from work-engaging position, and means influenced by the oppositely directed movements of the presser-foot for pulling successively reserve lengths of needle-thread from the thread supply.

9. In a sewing machine, in combination, a frame, stitch-forming mechanism including a reciprocating thread-carrying needle and loop-taking means coordinated therewith, a member movable in opposite directions carried by said frame, a thread pull-off element, and means under control of said member for causing said thread pull-off element to pull successively reserve lengths of needle-thread from the thread supply during the oppositely directed movements of said member.

10. In a sewing machine, in combination, stitch-forming mechanism including a reciprocating thread-carrying needle and loop-taking means coordinated therewith, a presser-foot movable between work-releasing and work-engaging positions, and means for pulling a reserve length of needle-thread from the thread supply when the presser-foot is moved from work-releasing to work-engaging position.

RUDOLPH J. SAILER.
